Primary Examiner—Alan P. Douglas*Assistant Examiner*—Rosemary K. Tarcza(74) *Attorney, Agent, or Firm*—Brinks Hofer Gilson & Lione(57) **CLAIM**

We claim the ornamental design for a battery, as shown and described.

DESCRIPTION

FIG. 1 is a top perspective view of a battery of the present invention;

FIG. 2 is a top view thereof;

FIG. 3 is a first side view thereof;

FIG. 4 is a second side view thereof;

FIG. 5 is a bottom view thereof;

FIG. 6 is a third side view thereof; and,

FIG. 7 is a fourth side view thereof.
